CLAIM

The ornamental design for a candy dispensing toy, as shown and described.

DESCRIPTION

FIG. 1 is a top perspective view of a candy dispensing toy showing my new design.

FIG. 2 is a bottom perspective view thereof;

FIG. 3 is a front view thereof;

FIG. 4 is a rear view thereof;

FIG. 5 is a left view thereof;

FIG. 6 is right view thereof;

FIG. 7 is a top view thereof; and,

FIG. 8 is a bottom view thereof.

1 Claim, 4 Drawing Sheets
